UNITED STATES PATENT OFFICE

150,124

DESIGN FOR AN HOURGLASS FRAME OR SIMILAR ARTICLE

Charles Fischett, South Ozone Park, N. Y.

Application February 28, 1947, Serial No. 137,225

Term of patent 14 years
(Cl. D42—7)

To all whom it may concern:

Be it known that I, Charles Fischett, a citizen of the United States, residing at South Ozone Park, Long Island, New York, have invented a new, original, and ornamental Design for an Hourglass Frame or Similar Article, of which the following is a specification, reference being had to the accompanying drawing, forming part thereof.

Fig. 1 is a top plan view;

Fig. 2 is a front elevational view; and

Fig. 3 is a side elevational view of an hourglass frame or similar article showing my new design.

I claim:

The ornamental design for an hourglass frame or similar article, substantially as shown.

CHARLES FISCHETT.
